UNITED STATES PATENT OFFICE.

WILLIAM G. ESTEP, OF DUQUESNE, PENNSYLVANIA.

FAUCET.

Application filed April 16, 1925. Serial No. 23,609.

To all whom it may concern:

Be it known that I, WILLIAM G. ESTEP, a citizen of the United States, residing at Duquesne, in the county of Allegheny and State of Pennsylvania, have invented a new and useful Faucet, of which the following is a specification.

This invention relates to faucets, one of its objects being to provide a structure of this type having a valve which will normally close under pressure, will always remain in firm engagement with its seat while closed, will not grind upon and be mutilated by the seat, and can be readily unseated against the action of fluid under pressure.

Another object is to provide a faucet the valve portion of which is readily accessible, can be easily cleaned and repaired, and will rarely get out of order.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a longitudinal section through the device, portions being broken away.

Figure 2 is a central vertical transverse section.

Referring to the figures by characters of reference 1 designates the body portion of the faucet from which extends a tubular arm 2 and a spout 3. The passage 4 in the arm 2 extends to a recess 5 which opens through the bottom of the body and extends under a partition 6 which separates the passage 4 from the passage 7 in the spout 3. This partition has an opening 8 through which communication is established between the two passages 4 and 7 and formed on the bottom surface of the partition and around the opening 8 is a rib 9 which constitutes a valve seat.

A screw plug 10 is insertible into the opening 5, the thread thereon engaging the lower portion of the wall of the opening or recess as shown at 11. The inner portion of this

plug is spaced from the wall of the recess 5 and the inner extremity of the plug is preferably substantially in the same plane with the lowest portion of valve seat 9. Said extremity is also spaced from although 60 supported close to the lower surface of partition 6.

Plug 10 has a recess 12 extending thereto from its inner end and seated in this recess is a spring 13 which yieldingly supports a valve 14 slidable in the recess 12. This valve is movable freely in the recess and has a packing disk 15 of fiber or other suitable material fastened to its upper surface so that spring 13 will thus hold the disk 70 normally pressed against seat 9, thereby to close communication through the opening 8. This position of the parts is clearly shown in Figure 2.

The body 1 has a boss 16 extending upwardly therefrom and interiorly screw threaded as indicated at 17. This boss is provided with a packing washer 18 and a screw cap 19. A stem 20 is mounted to slide and rotate within the gland and has a short 80 thread 21 engaging the threaded portion 17 of the boss. The outer end of the stem 20 has a handle 22 or the like whereby it can be rotated readily. The inner end of the stem is adapted to bear against the disk 85 15 or, if preferred, the middle portion of the valve 14.

By rotating stem 20 in one direction it is quickly moved upwardly so that spring 13 will move the valve against its seat. 90 Further rotation of the stem in the same direction will not rotate the valve. Instead the valve will remain upon its seat as the stem continues to move away from the valve. While the valve is against its seat the water pressure will be against the periphery thereof and will not be able to force the valve against the action of its spring. Thus there is no danger of leakage. By giving a slight turn to the stem 100 20 in the opposite direction it will be moved against the valve and unseat it so that water will escape in a thin film over the inner end of the plug 10 and between the valve and seat 9. Obviously this construction permits a minute control of the water flow and as there is practically no wear upon the parts, the faucet can be used indefinitely.

The valve can be readily removed for inspection, etc., simply by unscrewing the plug 110

10 and, should it be desired to remove the stem 20 it would merely be necessary to detach the cap 19.

What is claimed is:

- 5 1. A faucet having an outlet passage and an inlet passage, there being an apertured partition between the passages, said inlet passage communicating with a recess opening through the bottom of the faucet, a
- 10 screw plug detachably seated in the open bottom of the recess and projecting into said recess close to the partition, said plug having a recess extending there into from its inner end, a spring pressed valve slidable
- 15 within the recessed plug, a seat upon the partition extending around the aperture therein and normally engaged by the valve, and a screw stem separate from the valve and engaging the body of the faucet, said
- 20 stem projecting through the aperture in the partition and adapted to engage the valve.
2. A faucet having an outlet passage and an inlet passage, there being a partition between the passages provided with an aperture, the inlet passage communicating with a recess under the partition opening through

the bottom of the faucet, a valve seat on the bottom of the partition extending around the aperture therein, a screw plug detachably seated in the open bottom of the 30 recess, the inner portion of said plug being close to but spaced from the partition and the wall of the recess, there being a recess extending into the plug from the inner end thereof, a spring pressed valve slidably 35 mounted in the recessed plug and normally engaging the seat, said plug and partition cooperating to direct fluid in a thin film against the valve and under the seat when the valve is open, a threaded stem engaging 40 the body of the faucet and separate from but movable against the valve to unseat it, said stem extending through the opening in the partition, and means for rotating the stem.

In testimony that I claim the foregoing as my own, I have hereto affixed my signature in the presence of two witnesses.

WILLIAM G. ESTEP.
